INKSTAND

Herman Frederick Krueger, Los Angeles, Calif.

Application October 30, 1939, Serial No. 301,992

1 Claim. (Cl. 120—59)

My invention concerns improvements in ink stands of the type in which ink is supplied from a main storage reservoir to a pool into which the pen is dipped and, in general, it concerns improvements upon the invention disclosed in my Patent Number 2,178,861, dated November 7, 1939.

A difficulty which I have found to be present in prior art ink stands embodying a main reservoir in communication with a dispensing pool, resides in the fact that, due to increases in temperature, the ink supply expands to a point which causes overflow of the device. Another shortcoming is that when such devices are tilted from the horizontal, the dispensing ink pool is apt to overflow. Those shortcomings have proved to be seriously objectionable features in the type of ink stand to which my invention relates.

I aim to cure those shortcomings by providing an ink stand which includes, in association with the ink dispensing pool, an expansion chamber to take care of any overflow caused by temperature changes.

Another object is to provide an improved passageway construction between the outlet of the main reservoir and the inlet to the dispensing pool, which will trap and prevent ink from overflowing when the device is tipped from the horizontal.

Those and other objects will become clear from the following detailed description of one preferred form which my invention may take, for which purpose I refer to the accompanying drawing, in which:

Fig. 1 is a plan view;

Fig. 2 is a section on line 2—2 of Fig. 1;

Fig. 3 is a section on line 3—3 of Fig. 1;

Fig. 4 is a horizontal section on line 4—4 of Fig. 3; and

Fig. 5 is a fragmentary section on line 5—5 of Fig. 1.

Referring now to the drawing, the numeral 5 designates a base having a central cavity 6 into which snugly fits an inner casing 10 provided with a pair of opposite side recesses 11, a central ink receiving recess 12, a curved wall portion 15 forming a passageway 16 communicating from the central recess 12 to a larger recess 17 in casing 10. The latter recess communicates with side recesses 11 through openings 18. The bottoms of the recesses 11, 12, 17 and passageway 16 are coplanar.

A cover plate 20 is mounted in the annular recess 21 in the body, said cover plate having a central opening 23 into which snugly fits a con-

tainer 25 whose bottom wall 26 tapers to a restricted outlet orifice 27. The top wall 30 of the container has a round neck portion 31 annularly threaded at 32 to receive a screwthreaded cap 35. The top of the neck has an annular recess 37 into which fits a soft rubber, cork or other suitably resilient packing washer 38. Said washer is adapted to be compressed between the underface of the top wall of the cap and the shoulder 39 provided on the neck by recess 37. The cap presents a central, downwardly opening socket member 40 into which fits the top end of a valve stem 42. The bottom end of the stem 42 is enlarged and projects through orifice 27 to provide a tapered valve 44 adapted to be urged against orifice 27 as a seat by coil spring 46 which seats at its bottom end within a small recess 47 formed in the bottom of casing member 10.

Stem 42 is of such length that when cap 35 is screwed down onto neck 31 valve 44 is moved off its seat to permit ink to flow into the central recess 12 through orifice 27, and, from that recess, through passageway 16 to recess 17, thence 25 through openings 18 into side recesses 11, with which the flared pen holding members 52 communicate. The ink level L of the ink pool in said recesses and passageway is maintained substantially even with the bottom surface of outlet 27, said pool being exposed to atmospheric pressure through the openings 53 in members 52. As the ink is used, it is automatically replenished from the main container 25.

As best shown in Figs. 4 and 5, I provide for 35 expansion of the ink in chamber 17 as, for instance, when such expansion is caused by increased temperatures. The top portion of casing member 10 adjacent chamber 17 is hollowed out to provide an expansion chamber 60 whose bottom 60a is substantially even with the normal ink level L, said chamber 60 being in communication with chamber 17 so that as the ink in chambers 11, 12, 17 and passageway 16 expands, 45 causing the ink level to rise, the overflow flows into the expansion chamber 60, thus preventing it from overflowing the device through the openings in the pen holding members 52.

As will be best seen in Fig. 4, wall 15, which forms passageway 16, is comprised of a continuous circular wall provided by concentric segments 15a, 15b connected together by a reversely curved portion 15c. Thus passageway 16 is likewise curved so that if the ink stand is tilted from the horizontal, the greater portion of the

ink within chamber 12 and passageway 16 is trapped by wall 15.

While, in the foregoing description, I have resorted to various details of structure and association of parts, I wish it understood that I do not thereby confine my invention to such specific details. Rather, various modifications and adaptations may be made within the broader scope of the invention as defined by the appended claim.

10

reservoir and an ink dispensing chamber, spaced concentric circular walls separating the reservoir from the chamber, said walls forming a circuitous passageway therebetween, another wall 5 between the outermost of the circular walls and the dispensing chamber and a communication opening in said other wall, said circuitous passageway terminating at a point laterally spaced from said opening.

I claim:

In an ink stand, a base having therein an ink
